JOSEPH CROMPTON, OF LITTLE FALLS, NEW JERSEY.

Letters Patent No. 63,706, dated April 9, 1867.

IMPROVEMENT IN BOLTS AND BOLT-HEADS.

The Schedule referred to in these Letters Patent and making part of the same.

TO ALL WHOM IT MAY CONCERN:

Be it known that I, JOSEPH CROMPTON, of Little Falls, in the county of Passaic, State of New Jersey, have invented a new and useful Improvement in Bolts and Bolt-Heads, and that the following is a full and exact description thereof, which will enable those skilled in the art to make and use the same, reference being had to the accompanying drawing, forming part of this specification, in which—

Figure 1 shows the bolt, with its appurtenances, applied to secure a "patch," marked B, upon the side of a boiler.

Figure 2 is an axial section of the bolt and its appurtenances, showing also a section of the boiler-plate and patch.

Figure 3 is an elevation, showing the bolt-head, the eccentric-collar, and the patch, the boiler-plate being supposed to be removed, but its outlines being represented in red.

Figure 4 is a plan view of the small end of the bolt.

The object of this invention is to provide a bolt which will enable one to attach and secure one plate or article to another in cases where the inner side of the latter is inaccessible, so that one cannot get in a position to apply a rivet. In order to illustrate my invention, I have selected the example of a steam boiler, to which, while it is inaccessible, or while hot, a "patch" is to be applied to cover a fracture, and which "patch" consequently must be applied from without.

The letter A designates a portion of the side or plate of a steam boiler, and B is part of a "patch," which is to be secured thereto. Holes are made through the boiler-plate at the several places where the bolts which secure the patch are to be inserted, and holes of like size and at equal distances apart are made in the "patch." The drawing shows one such hole through the boiler-plate and patch. The letter C designates a bolt used for uniting the patch to the boiler. The bolt has a screw-thread cut on its body to receive a nut, E. It has an eccentric-head, F, whose diameter is about the same as that of the holes in the boiler and patch; or, its diameter may be a very little less, in order to allow the head to be put through them. When the head has been pushed through far enough to clear the boiler-plate, the bolt is brought up against the edges of the holes, so as to make the shoulder or eccentric-enlargement of the head, clearly shown in the drawing, overlap the boiler-plate. In order to retain the bolt-head in this position, an eccentric-collar, H, (one side being thicker than the other,) is inserted at the same time with the bolt, or else after it has been got in the holes; and before it is brought up to its place. In this example the collar H does not form a complete circle, but is crescent-shaped, as is seen in fig. 3. The thickest part of the collar is put opposite the eccentricity of the head F by turning the bolt after it and the collar are pushed in far enough, so as to cause its shoulder to overlap the edge of the hole in the boiler, the collar being made of such dimensions as to fill the space between the body of the bolt and the sides of the holes. In order that the workman or operator may know the exact position of the head, and whether its enlarged side is diametrically opposite the thicker part of the collar, I make an indentation, G, or other mark on the end of the bolt near the side on which the enlargement or eccentricity of the head F is located, by observing which indentation or mark, and causing it to be diametrically opposite the thickest part of the collar, one can make sure that the bolt-head is in its proper place. The collar and bolt together are of such size or dimensions as to fill the holes as snugly as possible, in order to prevent leakage as much as possible. The collar can be made of copper or iron, or other suitable material. Copper is suitable for the purpose, because it expands readily, and therefore will aid in making a tight joint about the bolt. After the bolt and collar are in place, a washer, D, of copper, or other suitable material, is put on the bolt, and the nut E is then screwed tight, so as to draw the patch B and the bolt-head snugly against the opposite surfaces of the boiler-plate. In order to insure against leakage the bolt may have a fillet of tow or other fibrous packing wound around it between the end of the eccentric-collar and the bolt-head; or, the collar may be made shorter than the united thickness of the boiler-plate and the patch; and the annular space thus left between the circumference of the bolt and the sides or edge of the hole in the patch may be occupied by a ring of copper or other soft metal, which can be jammed up by the tightening of the nut, and expanded so as to close the joint; or, both these modes of packing the joint may be adopted. The patch B is united to the boiler in this manner at as many places as is found

necessary and desirable. This mode of uniting two pieces of metal or other material can be applied and used in many other places and circumstances besides the one described in this example.

Having thus described my invention, what I claim, and desire to secure by Letters Patent, is—

1. The eccentrically-headed screw-bolt C, in combination with the nut E and the eccentric-collar H, placed around the bolt, substantially as described.
2. I also claim the combination of the bolt C, having an eccentric-head, F, with the eccentric-collar H, or its equivalent, the patch or plate B, and the boiler-plate, or article to which the plate B is united, substantially as shown.

JOSEPH CROMPTON.
